US00D809541S

(12) **United States Design Patent** (10) Patent No.: **US D809,541 S**
Makowski et al. (45) Date of Patent: ** Feb. 6, 2018

(54) **DISPLAY WITH GRAPHICAL USER INTERFACE**

(71) Applicant: **Sartorius Stedim Biotech GmbH**, Göttingen (DE)

(72) Inventors: **Kai Makowski**, Spangenberg (DE); **Reinhold Ried**, Melsungen (DE); **Hans-Juergen Geyer**, Kassel (DE)

(73) Assignee: **Sartorius Stedim Biotech GmbH**, Göttingen (DE)

(**) Term: **15 Years**

(21) Appl. No.: **29/573,788**

(22) Filed: **Aug. 9, 2016**

Related U.S. Application Data

(62) Division of application No. 29/512,761, filed on Dec. 22, 2014, now Pat. No. Des. 776,143.

(57) **CLAIM**

The ornamental design for a display with graphical user interface, as shown and described.

DESCRIPTION

This application contains at least one drawing executed in color. Copies of this patent or patent application publication with color drawing(s) will be provided by the Office upon request and payment of the necessary fee.

FIG. 1 is a front view of a first embodiment of a display with graphical user interface according to the present disclosure; and,

FIG. 2 is a front view of a second embodiment thereof. The broken line showing the display with graphical user interface is included for the purpose of illustrating environmental structure and forms no part of the claimed design.

1 Claim, 2 Drawing Sheets
